tical Company, Rochester, N. Y., a corporation
of New York

Application December 15, 1951, Serial No. 17,747

Term of patent 14 years

(Cl. D57—1)

To all whom it may concern:

Be it known that we, Raymond F. E. Stegeman and Fred G. Gay, Jr., citizens of the United States and residents of the town of Greece, county of Monroe, and State of New York, have invented a new, original, and ornamental Design for Goggle Front, of which the following is a specification, reference being had to the accompanying drawing, forming a part hereof.

Fig. 1 is a front perspective view of a goggle front, showing our new design.

Fig. 2 is a rear elevational view thereof.

Fig. 3 is a side elevational view thereof.

We claim:

The ornamental design for a goggle front, substantially as shown.

RAYMOND F. E. STEGEMAN.
FRED G. GAY, JR.
